UNITED STATES PATENT OFFICE.

FRANK ENOS, JR., OF NORWICH, CONNECTICUT, ASSIGNOR TO THE NORWICH AUTOMATIC FEEDER COMPANY, OF NORWICH, CONNECTICUT, A CORPORATION OF CONNECTICUT.

DRINKING-FOUNTAIN FOR POULTRY.

1,158,035.

Specification of Letters Patent.

Patented Oct. 26, 1915.

Original application filed August 12, 1914, Serial No. 856,465. Divided and this application filed January 4, 1915. Serial No. 440.

To all whom it may concern:

Be it known that I, FRANK ENOS, Jr., a citizen of the United States, residing at Norwich, county of New London, State of Connecticut, have invented certain new and useful Improvements in Drinking-Fountains for Poultry; and I do declare the following to be a full, clear, and exact description of the invention, such as will enable others skilled in the art to which it appertains to make and use the same.

This invention relates to certain new and useful improvements in drinking fountains for poultry, and relates more particularly to a fountain of the type in which a lower heater device acts as the support for the upper reservoir in which latter the water is kept and maintained warm by the heater so as to prevent freezing in cold weather.

20 The present invention is a division of an application filed August 12, 1914, Serial No. 856,465.

The primary object of the invention is to provide means whereby the reservoir may be easily and quickly removed from and applied to the heating means, and more specifically to provide means whereby the reservoir will be automatically locked to the heating means when the reservoir is placed in proper position on top of the heating means.

In the drawings: Figure 1 is a side elevation of the invention; Fig. 2 is an enlarged detail view, partly in section of the gravity hooks and Fig. 3 is a fragmentary rear elevation showing two of the latches.

The heater structure which forms the base for the fountain is designated 1 in the drawings, and receives thereon the reservoir 2, the latter having a groove 3 in its bottom to conformably receive the annular top edge 4 of the heater 1. A preferably circular flange 5 is secured to the heater 1, in any suitable manner, as by riveting at 6 and extends outwardly beyond the periphery of the reservoir 2.

A plurality of latches or hooks of the gravity type indicated at 7 are pivoted at 8 to ears 9 provided on the reservoir 2, the free lower ends of the latches being formed

so as to engage beneath the flange 5, the latches having their free ends curved at 10 so that in placing the reservoir on top of the heater the curved portions of the latches will ride on the flange 5 and then by the action of gravity move to engage beneath the flange 5, thus automatically locking the reservoir to the heater.

The lower end portions of the latches are prevented from moving too far inwardly toward the reservoir, by the rib 11 on the base of the reservoir, so that when the reservoir is placed on the heater, the curved ends of the latches will overlie the flange 5 and will immediately engage the latter as soon as the reservoir is moved down on top of the heater. By providing a circular flange 5, it will be apparent that the reservoir can be placed on top of the heater at any point on the latter, that is to say no special alignment is necessary, save that of effecting register of groove 3 with the edge 4 of the heater, and in addition after the hooks or latches have been engaged with the flange 5, the heater and reservoir can be relatively rotated if desired without necessitating disengagement of the reservoir from the heater.

What is claimed is:

In combination with a water tank, a heater casing having a peripheral flange, said tank having a peripheral rib, a plurality of gravity operated latches having their upper ends pivotally connected to the tank above the rib so as to have their movement toward the tank restricted by engagement with the rib, the free ends of said latches being curved, said latches being adapted to swing by gravity into engagement with the rib and to disengage said rib upon engagement of the curved free ends thereof with the flange, whereby said latches successively and automatically disengage and engage the rib and flange, respectively when the tank is placed upon the heater.

In testimony whereof I affix my signature in presence of two witnesses.

FRANK ENOS, JR.
